US00D818683S

(12) **United States Design Patent** (10) **Patent No.:** **US D818,683 S**
Marvin et al. (45) **Date of Patent:** **** May 29, 2018**

(54) **SHOE MIDSOLE**

13/22; A43B 13/223; A43B 13/24; A43B

(71) **Applicant:** **Reebok International Limited**, London
(GB)

13/28; A43B 13/30; A43B 13/32; A43B

13/34; A43B 13/36

See application file for complete search history.

(72) **Inventors:** **William Marvin**, Canton, MA (US);
Matthew Montross, Middleboro, MA
(US)

(56)

CLAIM

The ornamental design for a shoe midsole, as shown and described.

DESCRIPTION

FIG. 1 is a side view of a shoe midsole showing the claimed design; and,

FIG. 2 is a bottom view thereof.

The broken lines in the figures show portions of the shoe midsole and environment that form no part of the claimed design.
